FOLDING CHAIR

Ralph A. O'Neill, Englewood, N. J.

Application June 3, 1952, Serial No. 291,509

17 Claims. (Cl. 155—142)

This invention relates to a folding or collapsible article of furniture, and more specifically comprehends a folding chair of novel construction.

An object of the invention is the provision of an article of furniture with folding means that effectively maintains the same in rigid, releasably locked assembly when in load-supported unfolded position whereby rocking or side-sway is substantially prevented.

Objects of the invention include a folding chair that is light in weight, structurally strong, and maintained erect without side-sway, springing or side-rocking when occupied by a person when in use; a folding chair that is readily and easily collapsible or foldable into compact arrangement for storage when not in use; a folding chair that combines ruggedness to wear, easy portability, lightness of weight, and precision locking into unfolded or usable position; a folding chair having its structural frame of extruded aluminum of a unit shape comprising two hollow cylindrical portions joined by a common web; a folding chair having a novel construction that insures stability without side-sway or rocking when in occupied use; an all-metal folding chair of rigid construction comprising a back frame having the extended side posts thereof constituting two forward legs of the chair, two other supporting leg members pivoted to the side posts of the back frame constituting two rear legs of the chair, and a seat frame having two side rails pivotally mounted on the side posts of the back frame and adapted to releasably engage by blade and slot connection into rigid unfolded position with the two rear legs of the chair.

Other objects of the invention will be apparent from the description, appended claims, and the drawing hereinafter, in which:

Figure 1 is a side elevation of the essential mechanical construction of the chair when in partially opened position, the view being an internal one, i. e. from the inside of the chair.

Figure 2 is a view in side elevation of the essential mechanical construction of the chair shown in Fig. 1 when in entirely open or unfolded position, ready for use.

Figure 3 is a view in side elevation of the construction shown in Figures 1 and 2, when the same is in entirely closed or folded position.

Figure 4 is a view looking in the direction of arrow 4 in Figure 3.

Figure 5 is a view looking in the direction of arrow 5 in Figure 3.

Figure 6 is a front end view of Figure 1 showing the attachment of the seat to the seat frame.

Figure 7 is a view along the line 7—7 of Figure 2.

Figure 8 is a view along the line 8—8 of Figure 2.

Figure 9 is a view along the line 9—9 of Figure 3.

Referring to the drawings the numeral 1 is a side post of the back frame, and is made of an extruded aluminum shape shown in cross-section in part of the view of Figures 8 and 9 and comprising two hollow seamless cy-

2

lindrical portions 2 and 2', and a connecting web 3. Passing through a slot in 2' and securely riveted to the web 3 by rivet 4 is the flat ear 5 having pivoted thereon a flat element 6 by the pivot pin 7. The element 6 is securely riveted to a rear leg 8 with rivet 9, two tongues of the element 6 extending into the hollow cylindrical portions of leg 8. The side post 1 has the seat side rail 10 pivotally mounted thereon through the medium of a flanged bridge element 11 which is riveted to the web 3 at points 12 and 13, the rail 10 having a headed pivot bolt 14 extending through the element 11, with a metal washer and peened head firmly pivotally mounting the rail 10 on the post 1 with the bridge 11 functioning as a bearing where it contacts the flat side of the rail 10. The side rail 10 is formed of the same extruded aluminum shape of the post 1 and has pivotally attached thereto at its web a flat link element 15 through the medium of a double-headed bolt 16 and washer therefor. The flat link element 15 is of arcuate shape and is provided with a notch or cut-out portion in the configuration of an angle defined by faces 17 and 18. The element 15 is pivotally attached to the rear leg 8 by the pivot pin 19. Rigidly fixed to the rear leg 8 by a bolt 20 is a bifurcated abutment element 21 which has two legs 22 and 23 separated by a slot 24. The leg 23 is longer than the leg 22 and has at the bottom thereof a flanged portion 25 which is normal to the web of leg 8 and fits snugly in the space between the cylindrical sides of the leg 8. As shown in Figures 1 to 4, the flange 25 of the leg 23 forms a stop or abutment for the cut-out face 17 of the link 15, and the side face 26 of the leg 23 forms a stop or abutment for the cut-out face 18 of the link 15. The slot 24 of the bifurcated stop element 21 is adapted to receive therein the terminal bladed end 27 of the seat rail 10. The bladed end 27 is formed by cutting away part of the cylindrical portion to leave an abutment edge or face 28 on the bladed end to contact the top face 33 of the slot 24 and to provide an abutting end face 29 of the cylindrical portion to contact the side wall 30 of the bifurcated element 21. The end face 31 of the leg 22 also forms a stop for the cylindrical portion 32 that has not been cut away and which extends lengthwise beyond the cut-away cylindrical portion of the side rail 10.

Referring now to Figure 6, this shows the attachment of the metal seat 34 to the seat side rail 10. As shown also in Figure 1, a metal angle element 35 has a depending convexly curved portion 36 fitting against the top cylindrical portion of the seat side rail 10 and a straight portion lying flat against the web below. Between the curved and flat configurated end of the metal angle element 35 and the top cylinder and web of side rail 10 lies the corresponding curved and flat configurated flange of the metal seat pan 34, with the top of the seat pan 34 extending over the top of the angle element 35, as shown at the right hand end of Figure 1 and in Figure 6. An exploded rivet 37 maintains the elements 34 and 35 fixedly secured to a cylindrical portion of the side rail 10. The metal seat pan 34 is attached at other points directly to the side rail 10 by exploded rivets (not shown) without the intervening angle element, which angle element is used at the front of the chair and extends transversely to the side rail 10.

The above description applies to one side of the chair, but it is clear that the other side is provided with a similar construction, the chair being formed of two back legs 8 and two forward legs which constitute lower extended portions of the posts 1 forming two sides of the back frame. Obviously, two side rails 10 form the seat frame with the transverse angle member 35 joining them. It is believed unnecessary to show the extreme terminals

of the legs or the top of the back frame, as any conventional construction of such may be used. The seat pan may have attached thereto any suitable seating material for comfort of the user and appearance of the chair.

The operation of the device is clear from the above description and the drawings. With the device in folded position as shown in Figure 3, a thrust downward of the seat clockwise will cause the parts to open into the unfolded position of Figure 2. In the fully open or usable position shown in Figure 2, a locking and fully supporting effect is obtained by blades 27 of the side rails 10 entering and interfitting with the slots 24 of the bifurcated abutment elements 21, the faces 28 contacting the top faces 33 of the slots, complemented by the faces 17 and 18 abutting the edge faces 25 and 26 respectively of the legs 23 of the bifurcated elements, and further complemented by the faces 29 of the terminated cylindrical ribs and the curved top surfaces 32 of the non-terminated cylindrical ribs abutting the edge faces 30 and 31 respectively. To fold the chair, an upward thrust against the seat counterclockwise causes disengagement for complete folding.

The result of this firm locking mechanism is a coordinated structure that does not wobble, rock, or sidesway, and at the same time provides necessary supporting strength for the load to be carried by the chair when occupied by the user.

The extruded unit shape having two cylindrical portions connected by a web which is used for the framework of the chair, is extruded preferably from aluminum and its alloys, but any other light metal or alloy having high strength commensurate with light weight may be used where lightness in weight is a requisite. In its broader aspects, the invention is not slavishly restricted to any specific metal, nor to the specific embodiment or mechanical details hereindescribed or disclosed, as modifications may be made by those skilled in the art without departing from the spirit and scope of the invention as defined in the appended claims.

I claim:

1. A folding chair having in combination a back frame, supporting means pivotally connected to said back frame, a seat frame pivotally connected to said back frame, and means defining a slot having spaced sides on said supporting means cooperating with means on said seat frame entering said slot in interfitting relationship to support the seat frame when in unfolded load-supporting position and removed from said slot when the seat frame is in folded position.

2. A folding chair having in combination a back frame, supporting means pivotally connected to said back frame, a seat frame pivotally connected to said back frame, and means on said supporting means cooperating with means on said seat frame in interfitting relationship to support the seat frame when in unfolded load-supporting position, and link means pivotally connected to said supporting means and pivotally connected to said seat frame to link the supporting means and seat frame together, said last named link means being engageable in abutting relationship with the means on the supporting means when the chair is in load-supporting position.

3. A folding or collapsible chair having a pair of front members defining at their top portions a back frame and at their bottom portions a pair of forward legs, a pair of rear members pivotally attached at their top portions to the front members in supporting relationship for the back frame and defining at their bottom portions a pair of rear legs, abutment means mounted on said rear members, said abutment means having slots therein, a pair of side members defining a seat frame, said side members having blade means at the ends thereof releasably engageable with the slots of the abutment means to support the seat when in open or unfolded position.

4. A folding or collapsible chair having a pair of front members defining at their top portions a back frame and

at their bottom portions a pair of forward legs, a pair of rear members pivotally attached at their top portions to the front members in supporting relationship for the back frame and defining at their bottom portions a pair of rear legs, abutment means mounted on said rear members, said abutment means having slots therein, a pair of side members defining a seat frame, said side members having blade means at the ends thereof releasably engageable with the slots of the abutment means to support the seat when in open or unfolded position, and link means pivotally connecting the side members with the rear members.

5. A folding or collapsible chair having a pair of front members defining at their top portions a back frame and at their bottom portions a pair of forward legs, a pair of rear members pivotally attached at their top portions to the front members in supporting relationship for the back frame and defining at their bottom portions a pair of rear legs, abutment means mounted on said rear members, said abutment means having slots therein, a pair of side members defining a seat frame, said side members having blade means at the ends thereof releasably engageable with the slots of the abutment means to support the seat when in open or unfolded position, and link means pivotally connecting the side members with the rear members, said link means having a cut-out portion the faces of which are engageable with side faces of the abutment means.

6. A folding chair formed of metallic structural members, said members having a configuration defined by two hollow cylindrical ribs connected by a web, said members comprising a back frame defining front legs extended therefrom, a seat frame, and rear leg members supporting the back frame, said rear leg members being pivotally connected to said back frame, the seat frame being pivotally connected to the back frame, link means pivotally connecting the seat frame to the rear legs, bifurcated abutment means fixedly secured to said rear leg members, the seat frame having a cylindrical rib of its structural member terminating a spaced distance from an end thereof to expose the web as a blade, the blade being movable into the bifurcated abutment means upon unfolding of the chair into load-supporting open position, and retractable from the bifurcated abutment means upon closing of the chair into folded position.

7. A folding chair formed of metallic structural members, said members having a configuration defined by two hollow cylindrical ribs connected by a web, said members comprising a back frame defining front legs extended therefrom, a seat frame, and rear leg members supporting the back frame, said rear leg members being pivotally connected to said back frame, the seat frame being pivotally connected to the back frame, link means pivotally connecting the seat frame to the rear legs, bifurcated abutment means fixedly secured to said rear leg members, the seat frame having a cylindrical rib of its structural member terminating a spaced distance from an end thereof to expose the web as a blade, the blade being movable into the bifurcated abutment means upon unfolding of the chair into load-supporting open position, and retractable from the bifurcated abutment means upon closing of the chair into folded position, said bifurcated abutment means having a long leg and a short leg, the vertical face of the terminated cylindrical rib and the curved top surface of the other cylindrical rib adjacent to the web contacting respective side surfaces of the short leg of the bifurcated abutment means.

8. A folding chair formed of metallic structural members, said members having a configuration defined by two hollow cylindrical ribs connected by a web, said members comprising a back frame defining front legs extended therefrom, a seat frame, and rear leg members supporting the back frame, said rear leg members being pivotally connected to said back frame, the seat frame being pivotally connected to the back frame, link means

pivottally connecting the seat frame to the rear legs, bifurcated abutment means fixedly secured to said rear leg members, the seat frame having a cylindrical rib of its structural member terminating a spaced distance from an end thereof to expose the web as a blade, the blade being movable into the bifurcated abutment means upon unfolding of the chair into load-supporting open position, and retractable from the bifurcated abutment means upon closing of the chair into folded position, the vertical face of the terminated cylindrical rib and the curved top surface of the other cylindrical rib adjacent to the web contacting respective side surfaces of the short leg of the bifurcated abutment means, said link means having an angular cut-out portion defining face edges which contact respective face edges of the long leg of the bifurcated abutment means when the chair is in load-supporting position.

9. The folding chair defined in claim 6 in which the metallic structural members are of extruded aluminum.

10. A folding chair formed of metallic structural members, said members having a configuration defined by two hollow cylindrical ribs connected by a web, said members comprising a back frame defining front legs extended therefrom, a seat frame, and rear leg members supporting the back frame, said rear leg members being pivotally connected to said back frame, the seat frame being pivotally connected to the back frame, link means pivotally connecting the seat frame to the rear legs, bifurcated abutment means fixedly secured to said rear leg members, the seat frame having a cylindrical rib of its structural member terminating a spaced distance from an end thereof to expose the web as a blade, the blade being movable into the bifurcated abutment means upon unfolding of the chair into load-supporting open position, and retractable from the bifurcated abutment means upon closing of the chair into folded position, a metal seat on said seat frame attached to a cylindrical rib by exploded rivet means passing into the hollow of the rib.

11. A folding chair formed of metallic structural members, said members having a configuration defined by two hollow cylindrical ribs connected by a web, said members comprising a back frame defining front legs extended therefrom, a seat frame, and rear leg members supporting the back frame, said rear leg members being pivotally connected to said back frame, the seat frame being pivotally connected to the back frame, link means pivotally connecting the seat frame to the rear legs, bifurcated abutment means fixedly secured to said rear leg members, the seat frame having a cylindrical rib of its structural member terminating a spaced distance from an end thereof to expose the web as a blade, the blade being movable into the bifurcated abutment means upon unfolding of the chair into load-supporting open position, and retractable from the bifurcated abutment means upon closing of the chair into folded position, a metallic angle section extending transversely on said seat frame, a seat on said seat frame, the seat and said angle section being secured to a cylindrical rib of said seat frame by exploded rivet means passing through the rib into the hollow thereof.

12. A folding chair including in combination a back frame having extensions thereof defining a pair of forward legs, a pair of rear legs pivotally connected to said back frame, an abutment member rigidly secured on each

of said rear legs, each of said abutment members having a slot therein, a seat frame including two side rail members each pivotally mounted respectively on the said forward legs at points substantially midway of the side rails, a link member pivotally connected at one end to each of said rear legs respectively at a point spaced below said abutment member and pivotally connected at the other end to a side rail at a point between said midway pivotal connection of a side rail and said abutment member, each of the side rail members having a flat bladed terminal engageable in each of the slots of the abutment members respectively, and each of the link members having a cut-out portion conforming to the sides of each abutment member, whereby upon unfolding the chair into load-supporting open position, the seat frame is securely locked in position.

13. An article of furniture having a collapsible or foldable unit comprising two pivotally connected members, one of said members having a blade-receiving slot associated therewith, a third member pivotally connected to the other of said members, and blade means on the third member in interfitting engagement with the blade-receiving slot when the unit is in unfolded position, said blade means on the third member being out of engagement with the blade-receiving slot when the unit is in folded position.

14. An article of furniture having a collapsible or foldable entity comprising two pivotally connected members, an abutment having a slot having spaced sides therein on one of said members, a third member pivotally connected to the other of said members, and means on said third member releasably engageable in interfitting relationship with the slot of the abutment.

15. An article of furniture having a collapsible or foldable entity including two pivotally connected members, an abutment having a slot having spaced sides therein on one of said members, a third member pivotally connected to the other of said members, a link pivotally connected to the third member and to the member having the abutment thereon, and means on the third member releasably engageable with the slot of the abutment in interfitting relationship.

16. An article of furniture including a supporting frame element of an extruded aluminum unit shape having a configuration defined by two seamless cylindrical hollow ribs integrally connected by a web.

17. As a new article of manufacture, an extruded aluminum structural supporting frame element having a unit shape defined by two elongated seamless cylindrical hollow ribs integrally connected by a web.
